(57) **CLAIM**

The ornamental design for a reclined swing, as shown and described.

DESCRIPTION

FIG. 1 is a perspective view of a reclined swing showing my new design;

FIG. 2 is a front elevation view of the reclined swing of FIG. 1;

FIG. 3 is a rear elevation view of the reclined swing of FIG. 1; FIG. 4 is a side view of the reclined swing a of FIG. 1, the other side view of this reclined swing would be a mirror image of this view;

FIG. 5 is a top view of the reclined swing of FIG. 1; and, FIG. 6 is bottom view of the reclined swing of FIG. 1. Note that the dashed lines shown in these drawings do not form part of the claimed invention.
